UNITED STATES PATENT OFFICE.

JOSEPH L. WRIGHT, OF CLEVELAND, OHIO, ASSIGNOR, BY MESNE ASSIGNMENTS, TO
EDWARD E. CLEMENT, OF WASHINGTON, DISTRICT OF COLUMBIA.

TELEPHONE-EXCHANGE SYSTEM.

1,168,259.

Specification of Letters Patent. Patented Jan. 11, 1916.

Application filed October 15, 1908; Serial No. 457,929. Renewed June 2, 1915. Serial No. 31,790.

To all whom it may concern:

Be it known that I, JOSEPH L. WRIGHT, a citizen of the United States, residing at Cleveland, in the county of Cuyahoga and State of Ohio, have invented certain new and useful Improvements in Telephone-Exchange Systems, of which the following is a specification, reference being had therein to the accompanying drawing.

10 My invention relates to telephone exchange systems and has for its object the provision of means whereby the duration of a telephonic conversation may be accurately recorded, and the operator notified when a 15 predetermined time has elapsed.

The invention contemplates the employment of any desired circuits, and may be applied to automatic as well as manual systems. Briefly stated it comprises an indicator normally at zero position, and a motor or driving shaft with which the indicator is engaged at the beginning of a conversation, as soon as the connection through the central office apparatus is completed. An 20 alarm or signal lamp is so arranged that after the indicator has been driven for a predetermined length of time or through a predetermined length of travel, the operator will be notified. This provision is especially 25 useful where charges are based upon the duration as well as the number of conversations. Thus, for example, in toll work, it is common to make a fixed charge for each given connection for a period of three 30 minutes or less, with an extra charge for each additional minute. My indicator being applied to the toll operator's cord-circuits, will automatically notify her at the expiration of three minutes, and will directly indicate or record the lapsed time both before 35 and after that.

My invention is illustrated in the accompanying drawing in which—

Figure 1 is a diagram showing two subscribers' telephone lines and central office apparatus for interconnecting them.

Figs. 2, 3 and 4 are details of apparatus.

In Fig. 1, A and A' are subscribers' stations connected to the central office by lines 50 1, 2, 3, 4, each line being provided with the usual line relay R, cut-off relay R', lamp L, and answering jack J. There may also be multiple jacks but the same are not shown, as they form no part of the present invention.

P and P' are an answering and a calling plug respectively, connected by the cord conductors 5—6 and 7—8 broken by the condensers C, and having the central office battery B bridged across them by way of the 60 conductors 9, 10, 11, 12, 13, and 9, 10, 14, 15, 16, 17.

L' and L² are the answering and calling supervisors controlled by the tip relays R² and R³ respectively, and supplied with current when the plugs are inserted in the jacks through the energization of the battery supply relays R⁴ and R⁵.

All the apparatus thus far described is of ordinary and well known construction and 70 arrangement and may be varied *ad libitum* without affecting my invention.

D is a constantly rotating shaft carrying a gear wheel d adapted to mesh with another gear wheel d' but normally disengaged 75 therefrom. The gear d' together with a disk d² carrying stud d³ and weighted at d⁴ to keep it normally in the position shown, is pivoted at d⁵ on the lower end of the lever d⁶ which itself is pivoted at d⁷ and has its 80 upper end carrying the armature d⁸ of the magnet D'. This magnet is included in a ground connection 18 from the front contact of relay R³, and since this relay becomes energized only when a called subscriber 85 answers, it follows that the magnet D' will be energized only at such times. When this magnet draws over the armature d⁸, it throws the lever arm d⁶ to the right, carrying with it the gear wheel d' and all its attachments. The gear wheel engages with its pinion d and is thereby rotated in the direction of the arrow, at a speed determined by the speed of rotation of the shaft D which is constant and so timed as to allow say 90 three minutes to elapse before the stud d³ will be carried through an arc of 180 degrees. When the wheel has been rotated this much, however, the stud is caused to close contact between a pair of springs S, thereby 100 closing the energizing circuit 19 of a special signal lamp L², which by its lighting indicates to the operator that the stated period of communication has expired and an extra charge must be made for time thereafter.

I may provide an electromagnet D² with a stop arm d⁹ and controlled through the branch circuit 20 by the relay R⁵, thus becoming energized as soon as the plug is inserted in a wanted line jack. This holds 105 110

- the gear d' against accidental displacement, and continues so to hold it after the called subscriber has finally hung up. Were it not for this provision, the weight d^4 would cause the wheel d^2 to return to zero position as soon as the magnet D' becomes deenergized, which would necessitate constant vigilance on the part of the operator to avoid missing a reading of the time. The reading of fractional parts of time after the first period has elapsed, or in fact the reading of any lapsed time, is by means of graduations on the edge of the wheel d^2 , suitably marked as shown in Fig. 2. These are preferably exposed to the operator one at a time, or otherwise designated in any well known manner, so that the operator can make the correct charge for the entire time consumed in the actual conversation by the two subscribers.
- 20 Figs. 3 and 4 show modifications in the method of controlling the timing wheel. Instead of having the magnet D' automatically energized when the called subscriber answers, I have shown it in Fig. 3 as becoming energized when the operator throws down the key K which she does upon perceiving that the lamp L^2 is extinguished, signifying that the called subscriber has answered. Fig. 4 shows a still simpler arrangement of apparatus without any actuated magnet but simply a manually operable lever having a handle d^{10} manipulated by the operator in a similar manner to the key K in Fig. 3.
- 35 I am aware that many changes may be made in the method of practising this invention, and in the details of the apparatus. I contemplate all such changes as fairly fall within the scope of my claims.
- 40 Having thus described my invention what I claim and desire to secure by Letters Patent is—
- 45 1. A message registering system comprising means for interconnecting parties for message transmission, a motor mechanism, a timing mechanism, a special signal controlled by the timing mechanism, means automatically actuated in completing a message connection to engage the timing mechanism with the motor and at the termination thereof to disengage it therefrom, and means also automatically actuated at the beginning of a message connection and remaining actuated thereafter, for retaining the timing mechanism in its actuated or indicating position, substantially as described.
- 50 2. In a telephone exchange system, an operator's cord circuit having sleeve and tip relays and a bridged battery, a constantly driven motor mechanism and a time indicator normally disengaged therefrom and adapted to be held in a zero or non-indicating position, an electromagnet adapted to throw said indicator into engagement with
- 55 the motor mechanism, a stop or detent for

said timing mechanism, an electromagnet controlling the same, and circuit connections for said electromagnets controlled by the cord circuit relays, whereby the time indicator will be started when a called subscriber answers, will be stopped when he finally hangs up his receiver, and will be returned to zero when the connection with his line is broken, substantially as described. 70

3. In a telephone exchange system, line 75 circuits and means for interconnecting the same, with a message registering device comprising a constantly driven motor, a timing device associated with but normally disengaged from said motor, a special signal controlled by said timing device after a predetermined interval of time from its starting, an electromagnet for engaging the timing device with the motor, and means automatically responsive to current flow in the use of 80 the connective circuit and lines, controlling said electromagnet, substantially as described. 85

4. In a telephone exchange system, line 90 terminals, a link circuit for interconnecting the same, a centralized battery and a supervisory relay connected with said link circuit, a constant speed motor, and a timing device carrying a circuit controller and adapted to engage said motor, an electromagnet controlling said engagement, a circuit for said electromagnet controlled by the supervisory relay, and a signal actuated by said circuit controller, substantially as described. 95

5. In a telephone exchange system, line 100 circuits, a link circuit for interconnecting the same, a relay associated with said link circuit and becoming energized when the link is brought into connection with a line, a second relay associated with the link circuit 105 and responsive to current flow in the connected line, a motor mechanism, a timing device normally disengaged therefrom, an electromagnet controlled by the first link circuit relay and adapted when energized to 110 maintain the timing device immovable, and an electromagnet controlled by the second link circuit relay and adapted when energized to disengage the timing device from its holding means and engage it with the 115 motor, whereby the initial connection of a link with a line will set the holding magnet, but will produce no effect upon the timing device, the response of the called subscriber will throw the timing device into engagement with the motor and start it to running, the cessation of current flow when the subscriber finishes his conversation will disengage the timing device from the motor and cause it to engage its holding device, 120 and finally when the indication has been read, the disengagement of the link circuit terminals from the line terminals will release the timing device and permit it to resume a normal or zero position. 125

6. In a telephone exchange system, an operator's cord circuit having sleeve and tip relays and a bridged battery, a time indicator biased to and normally occupying a zero indicating position but adapted to be driven from said position to other indicating positions, an operating circuit for the indicator under the control of the tip relay, whereby the indicator is started when a called subscriber answers and will be stopped when he finally hangs up his receiver, and a detent
- 5
- 10
- for said timing mechanism under the control of the operator whereby the indicator is held in the indicating position which it occupies when stopped as aforesaid until released by ¹⁵ act of the operator.
- In testimony whereof I affix my signature in presence of two witnesses.
- JOSEPH L. WRIGHT.
